UNITED STATES PATENT OFFICE.

ANTHONY RHENSTROM, OF KENOSHA, WISCONSIN.

BED-SPRING FABRIC.

1,405,868.

Specification of Letters Patent. Patented Feb. 7, 1922.

Application filed April 5, 1919. Serial No. 287,871.

To all whom it may concern:

Be it known that I, ANTHONY RHENSTROM, a citizen of the United States, residing in Kenosha, in the county of Kenosha 5 and State of Wisconsin, have invented a new and useful Improvement in Bed-Spring Fabrics, of which the following is a specification.

This invention relates in general to bed-spring fabric, and has more particular reference to bed-spring fabric of the rectangular link type and provided with links having legs composed of two strands of wire arranged close together and connected at 15 one end by an eye and provided at the other with hooks for engagement with other links of the fabric.

In the construction of fabric of this character it is not infrequently the custom to 20 provide links of the general character above outlined arranged with the hooks of one link engaged in the eye of the one next adjacent to form a chain or strand extending from one end of the fabric to the other 25 and to cross-connect these chains by links hooked merely in the eyes of the links of the chains. It has been found in practice that difficulty is experienced in preventing the cross-connecting links from sliding 30 down out of the eyes and engaging the legs. the evil of such arrangement is immediately apparent when it is considered that this destroys the normal arrangement of the 35 links consequently marring the visual effect of the fabric and also places undue strain on these cross-connecting links, for the distance between the legs is, or may be when weight is supported by the fabric, greater than the distance between the adjacent 40 sides of the eyes in which the displaced cross-connecting link is supposed to engage. Effort has been made to overcome this evil by twisting the legs about each other but this has placed undue twisting 45 strain on the wire and where galvanized wire is used in breaking the galvanized coating.

My present invention has for a principal object the provision of a link which will 50 insure against the displacement of links connected to it and which will not have the wires of the legs wrapped about each other and which will not by reason of its construction provide possibility of readily 55 breaking the galvanized surface.

Another important object of my present

invention is the provision of a fabric having links of this character which will be of simple and pleasing appearance and which can be made without requiring the complicated mechanical action of twisting the legs one about the other.

Numerous other objects and advantages of the invention will be apparent as it is more fully understood from the following 60 description when considered in connection with the accompanying drawing illustrating a preferred embodiment thereof.

On the drawing,

Figure 1 is a partial bottom plan view of 70 a bed-spring fabric embodying my present invention;

Fig. 2 is a section taken substantially on the line 2—2 of Fig. 1; and

Fig. 3 is a perspective view of one of the 75 links.

For the purpose of illustrating my invention I have shown on the drawing a part of a bed-spring fabric of the usual rectangular link arrangement and comprising longitudinal links 11 connected by cross-connecting links 12. The longitudinal links 11 are provided by bending a single piece of wire at its center to provide a round or other shaped eye 13, and legs 14 arranged closely 80 together and preferably in substantial parallelism, each of these legs having turn-back hooks 15 at their free ends which hooks are engaged in the eye of a next adjacent link to arrange the links 11 in connected or 85 chained-section form as will be readily understood. The cross-connecting links 12 each consist merely of a single short piece of wire bent at each end into hooks 16 which hooks are engaged in the eyes 13 appropriately arranged to receive them.

My invention is illustrated in the present instance in the formation of the eye 13 and its relation with respect to the two legs 14. It will be noted that the eye is disposed at 100 a 180-degree angle with respect to the normal position the legs would assume were they merely bent around into parallelism to provide the eye. That is to say, the leg 14 at one side is connected with a point 17 of the 105 eye at the other side of the link, one leg passing over the other, and merely crosses as counterdistinguished from being bent or wrapped around the other leg. This construction places very little strain upon the 110 surface of the metal and very little upon the body. If desired the ends may, and prefer-

ably are, bent up at the eye, as will be seen in Fig. 3, to dispose them in the same plane, and this acts to further lock the links 12 against entrance between the legs.

5 It is thought that the invention and many of its attendant advantages will be understood from the foregoing description; and it will be apparent that various changes may be made in the form, construction, and arrangement of the parts without departing from the spirit and scope of the invention or sacrificing all of its material advantages, the form hereinbefore described being merely a preferred embodiment thereof.

15 I claim:

1. A link fabric for bed-springs, comprising longitudinal links bent at the center to form an eye and to arrange the legs of said links in parallelism, said legs being crossed at the eye to dispose the leg connecting at one side of the eye upon the opposite side of the leg connected with the other side of the eye.

2. A fabric for bed-springs having links composed of two legs arranged in close parallelism and connected at one end by an integral eye, the side of the eye connected with a leg being disposed at the opposite side of the link from said leg.

3. A link for a bed-spring fabric consisting of two legs extending from an integral eye at one end and overlying each other at the eye and in close parallelism throughout their length, the leg at each side being connected with the side of the eye on the opposite side of said leg.

4. A link for a bed-spring fabric comprising two legs arranged in close parallelism and connected at one end by an integral eye, the side of the eye connected with a leg being disposed at the opposite side of the link from said leg, said legs at the crossing point being bent to dispose said legs in the same horizontal plane when the fabric is arranged in the bed.

ANTHONY RHENSTROM.
